CLAIM

The ornamental design for a power tool, as shown and described.

DESCRIPTION

FIG. 1 is a top front perspective view of our new design.

FIG. 2 is a rear view thereof.

FIG. 3 is a bottom view thereof.

FIG. 4 is a front view thereof.

FIG. 5 is a left side view thereof.

FIG. 6 is a right side view thereof; and,

FIG. 7 is a top view thereof.
